UNITED STATES PATENT OFFICE.

HOWELL CHENEY, OF SOUTH MANCHESTER, CONNECTICUT.

NECKTIE.

1,264,271.

Specification of Letters Patent. Patented Apr. 30, 1918.

Application filed December 10, 1917. Serial No. 206,417.

To all whom it may concern:

Be it known that I, HOWELL CHENEY, a citizen of the United States, residing at South Manchester, county of Hartford, State of Connecticut, have invented a certain new and useful Improvement in Neckties, of which the following is a full, clear, and exact description.

My invention relates to improvements in neckties and has for its object to produce a tie having separately formed neckband and tying end portions in which the neckband is connected to the tying end portions by an integral extension secured to the rear side 15 of the body of a tying end portion, and extending for a considerable distance along said rear side to the body portion thereof.

It further has for its object to produce such a tie in which there are, on opposite 20 sides of the tying end portions and secured thereto, extensions integral with the neckband portion, the extension on the rear side being much longer than the extension on the front side and extending to the body 25 portion of its tying end.

The following is a description of my invention, reference being had to the accompanying drawings, in which:

Figure 1 is a front view of a tie embodying my invention;

Fig. 2 is a rear view of the same;

Fig. 3 is a section of the upper end on the line 3—3, Fig. 2;

Fig. 4 is a section of the lower end on the 35 line 4—4, Fig. 2;

Fig. 5 is a separate view of the neckband portion with its extensions, and

Fig. 6 shows a modification.

Referring more particularly to the drawings, 40 1 is a neckband portion so constructed as to have two integral extensions at each of its two ends. I preferably make the portion of it which lies between the extensions tubular throughout, which can be done by 45 the weaving upon a suitable loom, or by sewing together the edges of two strips.

Upon the ends of the outer side of this tubular neckband short extensions, 2, 2' are formed and on the ends of the inner side of 50 said neckband longer extensions 3, 3' are formed. 4, 4' are the tying ends which are separately formed, and the small extremities 5, 5', of which are inserted within the tubular ends of the neckband portion. These 55 tying ends are made from cut fabric folded into two-ply form so that the edges lie along

the center of their rear faces. The small extremities of the two tying ends, being inserted within the tubular end portions of the neckband with the long extensions 3, 3' 60 adjacent to the inner faces of said tying ends, are secured to said neckband portion by stitches 6, 6' passing through both plies of the neckband portion and the intervening portions of the tying ends. The ends 65 3, 3' are then secured to the rear ply of the tying ends 4, 4' by stitches 7, 7' which pass through said rear ply and the ends 3, 3' without passing through the front side of the tying portions 4, 4'. In this way a tie 70 is produced in which the tying ends are firmly secured to the neckband portion and in which an extension, integral with the central part of the neckband portion, extends well down the rear plies of the tying 75 ends to the body portion thereof, and is secured thereto so as to not only make the connection between the several portions stronger, but to reinforce the tying ends so as to enable them to resist more strongly 80 any pull or strain which may be put upon them. The neckband portion is preferably with a smooth or satin finish so as to slip easily under the collar.

In order to further reinforce the tie and 85 add to its weight, I provide for each tying end a lining of soft material 8, 8', such as canton flannel, which is approximately the shape of the tying end, and has one end extending within an end of the tubular portion 90 of the neckband. When such a lining is used, I cause the stitches 7, 7' securing the extensions 3, 3' to the rear fold of the tying ends, to engage said lining. As an additional means of keeping the lining in place, 95 I secure it to the rear ply only of the tying ends by transverse lines of stitches 9, as shown in Figs. 2 and 4. This lining is cut straight, as distinguished from being cut on the bias, so as to resist, without substantial 100 stretching, any pull which may come thereon.

With a tie so constructed, the parts will be firmly secured and there will be little liability of the ties stretching or getting out 105 of shape when in use, and furthermore the neckband being thin and of an easy slipping character, will move easily within a turned-down collar when being applied.

The neckband portion shown in Figs. 1 to 110 4 is composed of a central portion 1 which is woven tubular, the extensions 2, 3 and 2',

3' being woven integral therewith and with separated selvage edges. Fig. 6 shows a modification in which the neckband is made up of two ribbons sewed together by stitches 5 10, 10 so as to form the tubular portion 1 of the neckband. The long extension 3' is essential to my invention, and for appearance and economy, I prefer to have the small extensions 2, 2' also.

10 The neckband portion herein described and the method of making the same are described and claimed in my pending application Serial No. 222,873, filed March 16, 1918.

15 As will be evident to those skilled in the art, my invention permits of various modifications without departing from the spirit thereof or the scope of the appended claims.

What I claim is:

1. A necktie, having a separately formed 20 tying end and a neckband portion, said neckband portion being two-ply adjacent to said tying end and having an elongated extension from one of its plies extending for a considerable distance beyond the other 25 ply and along the rear surface of its tying end to the body portion thereof, and stitches securing said plies to opposite sides of said tying end and said extension to the rear side of said tying end.

2. A necktie, having a folded two-ply 30 tying end portion, and a neckband portion secured thereto, said neckband portion having a tubular end portion within which said tying end extends, and having on one side 35 an elongated extension projecting beyond the other side and running along the rear of said tying end to the body portion thereof, and means for securing said tubular end portion and said extension to said tying 40 end.

3. A necktie, having a folded two-ply

tying end portion, a neckband portion secured thereto, said neckband portion having a tubular end portion into which said tying end extends, and having separated extensions along both sides of said tying end, the extension along the rear of said tying end extending to the body thereof, and being longer than the other extension, and stitches securing said extensions to said 50 tying end.

4. A necktie having a separately formed 55 tying end and a neckband portion, said neckband portion being two-ply adjacent to said tying end and having an elongated extension from one of its plies extending for a considerable distance beyond the other ply and along the rear surface of its tying end to the body portion thereof, stitches securing 60 said plies to opposite sides of said tying end and said extension to the rear side of said tying end, and a lining within said tying end also extending between the two plies of said two-ply portion and secured thereto and to said elongated extension. 65

5. A necktie having a separately formed 70 tying end and a neckband portion, said neckband portion being two-ply adjacent to said tying end and having an elongated extension from one of its plies extending for a considerable distance beyond the other 75 ply and along the rear surface of its tying end to the body portion thereof, stitches securing said plies to opposite sides of said tying end and said extension to the rear side of said tying end, a lining within said tying end also extending between the two plies of said two-ply portion and secured thereto and to said elongated extension, and transverse stitches securing said lining to the rear ply of said tying end. 80

HOWELL CHENEY.
